[57] CLAIM

The ornamental design for a freestanding modular display and divider wall, as shown and described.

DESCRIPTION

FIG. 1 is a front perspective view of a freestanding modular display and divider wall showing my new design;

FIG. 2 is a rear elevation view thereof;

FIG. 3 is a top plan view thereof; and,

FIG. 4 is a bottom plan view thereof.

The sides of the rearwardly-extending vertical panel are understood to be the same as the vertical panels shown in FIGS. 1 and 2.

1 Claim, 1 Drawing Sheet

FIG. 1

FIG. 2

FIG. 3

FIG. 4
